ELECTRICAL SYSTEM FOR COMPENSATING FOR LINE VOLTAGE VARIATIONS

Original Filed May 14, 1954

Fig. 1

Circuit diagram showing a power supply and a bridge rectifier. The power supply consists of a center-tapped transformer with secondary windings connected to +115 and -115. A bridge rectifier is connected across the +115 and -115 lines. The positive output of the bridge is connected to a series of components: a resistor (109), a capacitor (111), a resistor (108), and a capacitor (110). The output of this stage is connected to a vertical line labeled 'E'. This line 'E' is connected to a vertical line labeled '113' (top) and '114' (bottom). A resistor (115) is connected between the 'E' line and the '114' line. A vertical line labeled '116' is connected to the '114' line. A resistor (119) is connected between the '116' line and the '118' line. A vertical line labeled '120' is connected to the '118' line. A resistor (117) is connected between the '120' line and the '121' line. A vertical line labeled '122' is connected to the '121' line. A resistor (123) is connected between the '122' line and the '123' line. A vertical line labeled '124' is connected to the '123' line. A bridge rectifier (125) is connected between the '124' line and the '125' line. The '125' line is connected to a vertical line labeled 'C' (top) and 'C' (bottom). A resistor (127) is connected between the '125' line and the 'C' lines. A vertical line labeled '125' is connected to the 'C' lines. A resistor (128) is connected between the '125' line and the '124' line.

The diagram shows a bridge rectifier circuit. The top horizontal line is connected to terminal 90 on the left and terminal 94 on the right. The bottom horizontal line is also connected to terminal 90 on the left and terminal 94 on the right. The top-left branch contains a resistor 91 in series with a diode 92. The top-right branch contains a resistor 92 in series with a diode 94. The bottom-left branch contains a capacitor 95 in parallel with a center-tapped load. The bottom-right branch contains a capacitor 96 in parallel with a center-tapped load. The center-tapped load consists of two inductors 93 and 97, with two Zener diodes 93' and 97' connected across them in series with the center tap.

ELECTRICAL SYSTEM FOR COMPENSATING FOR LINE VOLTAGE VARIATIONS

Alexander Kusko, Newton Centre, Mass., assignor, by mesne assignments, to Basic Products Corporation, Milwaukee, Wis., a corporation of Wisconsin. Original application May 14, 1954, Ser. No. 429,731, now Patent No. 2,914,722, dated Nov. 24, 1959. Divided and this application May 1, 1959, Ser. No. 810,463. 3 Claims. (Cl. 323—2)

This invention relates to systems for compensating for variations in line voltage and other factors in an alternating current supply system and particularly to an arrangement for controlling a resonant circuit or static regulator in the system. This application is a division of copending application Serial No. 429,731, filed May 14, 1954, U.S. Pat. No. 2,914,722, which is a continuation-in-part of application Serial No. 339,141, filed February 26, 1953, now abandoned.

It is desirable in certain load circuits, such as lighting circuits, to provide arrangements to keep the current constant therein. The regulation of lamp current within a relatively narrow range is important in order to obtain reasonable lamp life and steady illumination. In resonant constant voltage to constant current transformation circuit means, such as the arrangement known as a monocyclic square, if the potential supplied thereto is constant, the current will be substantially constant, but if the potential varies, there will be a variation in load current.

One of the objects of the invention is to provide a circuit arrangement for a resonant circuit or static regulator system in which constant current will be supplied to the load regardless of variations, within limits, of line voltage and other factors.

Another object of the invention is to provide a circuit arrangement for a static type regulator of the resonant constant voltage to constant current type, wherein changes in the load current are utilized to apply corrections to saturable electro-magnetic devices in the system so as to maintain a constant applied current to the load.

In one aspect of the invention, a source of alternating current is connected to a resonant constant voltage to constant current transformation circuit, the output of said circuit being connected to the load which, for example, may be a lighting load. The resonant circuit may be a monocyclic square or a T circuit as will be described hereafter. A current sensing transformer or device is connected in the load circuit for producing a signal proportional to or a function of the load current. This signal is fed to a means comparing and amplifying any deviation therefrom to produce an indication signal. The means for producing the indication signal may be electromechanical, electronic, a magnetic amplifier or other similar device. The signal from the sensing and amplifying means is applied to the direct current winding of the saturable electro-magnetic means which in this application is a saturable transformer arrangement. The saturable electro-magnetic device concerned has at least a control and a gate or load winding associated with a common core.

These and other objects, features and advantages of the invention will become apparent from the following description and drawings, which are merely exemplary.

In the drawings:

FIG. 1 is a circuit arrangement employing a saturable transformer arrangement.

FIG. 2 illustrates another form of a resonant constant voltage to constant current transformation circuit which can be used in conjunction with a saturable transformer.

The arrangements involved are particularly concerned with supplying a constant load current to a load by a

2

resonant constant voltage to constant current transformation circuit independent of load impedance. The resonant constant voltage to constant current transformation circuit may be of the monocyclic square type wherein the input is connected to two sides of a bridge arrangement having capacitors in opposite legs of the bridge and reactors in the other legs. It is also applicable to a resonant constant voltage to constant current transformation circuit of the T type, as will be explained hereinafter. The T type has two reactors in series with a capacitor corrector across the line and between said reactors.

In these arrangements of resonant circuits, if the line voltage changes, the load current from the regulator will change proportionately, such being very objectionable. 15 Inasmuch as it is well known that line voltage will not stay constant and may change as much as 10% either way, there will be a constant change in load current. The supply frequency and the capacitance and reactances of the resonant constant voltage to constant current transformation device also may vary so that compensation therefor must be provided for efficient operation of the arrangement.

In one form of the invention, a monocyclic square is used which is tuned by resonating the reactance of the 25 inductors and capacitors that are in the monocyclic square. Changing one or the other sets of elements alone from resonance has been found to be an effective way to change current level over a limited range, for example, $\pm 10\%$ of the normal current. Change of $\pm 30\%$ in the reactance 30 of the reactor from the resonance value is sufficient to compensate for a $\pm 10\%$ change in line voltage in order to maintain a constant load current.

As an example of a circuit employing a saturable transformer, reference may be made to FIG. 1. The 35 monocyclic square G has reactors 108, 109 in two arms thereof and capacitors 110 and 111 in the other arms thereof, said monocyclic square being supplied by a source of alternating current. The output of the monocyclic square G is connected to saturable transformer 113, said saturable transformer having primary windings 114 and 115 connected to the opposite corners of the monocyclic square. Secondaries 116 and 117 are connected in load circuit 118 having the load diagrammatically illustrated at 119. The D.C. control winding 120 is inductively related to the windings of the saturable transformer 113. Current sensing transformer 121 has its primary 122 in the load circuit, the secondary 123 being connected to solenoid 124. Solenoid 124 may operate contact fingers 125 in devices such as the type known as "Regohm," having fingers which are connected to the resistor 125' thereof, such being an electro-mechanical comparing device. Other types of comparing devices can be used such as electronic tube or magnetic amplifiers as described in said copending application Serial No. 429,731.

Power for the control current may be supplied from the supply source 112 through a control transformer 127. Bridge rectifier 128 supplies control D.C. to the control 60 winding 120 in accordance with the current flowing in the load circuit 118.

Merely by way of example, the saturable output transformer 113 can be one built on a three-legged core with the control winding on the middle leg and the alternating 65 current winding on the outer two legs. One primary and one secondary alternating current coil can be placed on each outer leg, the two primary coils being connected in series and the two secondary coils connected in series in such a manner that there will be no induced line frequency voltage in the control windings.

In the embodiment shown in FIG. 2, input power can be supplied to terminals 90 by an input transformer to the

T type resonant constant voltage to constant current transformation circuit D. This circuit comprises reactors 91 and 92 in series with primary 93 of the output transformer 94. A capacitor 95 is connected at one point between reactors 91 and 92 and at its other side between primary 93 and terminal 90. A saturable transformer 94 is illustrated having a D.C. control winding 96.

The secondary 97 of the output transformer 94 can be connected to the load circuit at points E, E. A current sensing transformer in the load circuit then can be used to supply control voltage at C, C to the D.C. control winding 96 at C', C' of FIG. 2.

It should be apparent that variations may be made in the details of construction and arrangement without departing from the spirit of the invention except as defined in the appended claims.

What is claimed is:

1. In a system for compensating for variations in an alternating current supply system with respect to a power distribution load circuit, the combination including a resonant constant voltage to constant current transformation circuit means for feeding said load circuit, signal means directly connected to said load circuit producing a signal proportional to the load current in said load circuit, means comparing and amplifying deviation of said signal from a predetermined value to produce an indication signal, a saturable transformer means connecting said resonant circuit with said load circuit, said saturable transformer means having control winding means, and means connecting the control winding means of said saturable transformer means with said indication signal.

2. In a system for compensating for variations in an alternating current supply system with respect to a power distribution load circuit, the combination including a resonant constant voltage to constant current transformation circuit means feeding a load circuit, said resonant

circuit having a pair of reactors connected in series with the input and output and a capacitor across the input and between said reactor, a saturable transformer connected to said resonant circuit and having control winding means, 5 signal means directly connected to said load circuit producing a signal proportional to the load current in said load circuit, means comparing and amplifying deviation of said signal from a predetermined value to produce an indication signal, and means connecting the output of 10 said means comparing and amplifying said signal to said control winding means to maintain constant load current in the load circuit.

3. In a system for compensating for variations in an alternating current supply system with respect to a power 15 distribution load circuit, the combination including a resonant constant voltage to constant current transformation circuit means feeding a load circuit, said resonant circuit including a monocyclic square having four interconnected arms with capacitors in two opposite arms and 20 reactors in the other two opposite arms, a saturable transformer connected to said resonant circuit and having control winding means, signal means directly connected to said load circuit producing a signal proportional to the load current in said load circuit, means comparing and 25 amplifying deviation of said signal from a predetermined value to produce an indication signal, and means connecting the output of said means comparing and amplifying said signal to said control winding means to maintain constant load current in the load circuit.
